(57) **CLAIM**

The ornamental design for a vehicle service line holder, as shown and described.

DESCRIPTION

FIG. 1 is a first perspective view of a vehicle service line holder;

FIG. 2 is a second perspective view of the vehicle service line holder;

FIG. 3 is a front elevational view of the vehicle service line holder;

FIG. 4 is a rear elevational view of the vehicle service line holder;

FIG. 5 is a first side elevational view of the vehicle service line holder;

FIG. 6 is a second side elevational view of the vehicle service line holder;

FIG. 7 is a top plan view of the vehicle service line holder; and,

FIG. 8 is a bottom plan view of the vehicle service line holder.

The broken line shown in the drawings are for the purpose of illustrating portions of the article and form no part of the claimed design.
